L. W. THORSELL

PAPER ORNAMENT

Filed Feb. 3, 1922

INVENTOR.
Lars W. Thorsell
BY *H. G. Manning*
ATTORNEY

UNITED STATES PATENT OFFICE.

LARS WM. THORSELL, OF WATERBURY, CONNECTICUT.

PAPER ORNAMENT.

Application filed February 3, 1922. Serial No. 533,933.

To all whom it may concern:

Be it known that I, LARS WM. THORSELL, a citizen of the United States, and a resident of Waterbury, county of New Haven, and State of Connecticut, have invented certain new and useful Improvements in a Paper Ornament, of which the following is a specification.

This invention relates to suspended ornaments and more particularly to collapsible ornaments formed of a series of sheets or plies of paper or other flexible material.

One object of the invention is to provide an ornament of this nature in which the sheets or plies are originally assembled in a flat pile or pack, but may be readily opened out into the shape of a ball or other ornamental figure whenever desired.

Another object is to provide a collapsible ornament which will be simple, cheap to manufacture, and very efficient and durable in use.

With these and other objects in view, there has been illustrated on the accompanying drawings two forms in which the invention may be conveniently embodied in practice.

In the accompanying drawing,

Fig. 1 represents a perspective view of the first form of ornament, showing a series of paper disks assembled in a flat pack, and showing the cross disks in position.

Fig. 2 is a plan view of one of the cross disks shown in Fig. 1.

Fig. 3 is a side view of the ornamental ball formed by opening out the pack of attached disks shown in Fig. 1.

Fig. 4 is a view similar to Fig. 1, but showing a slightly modified form of the invention.

Fig. 5 is a plan view of one of the cross disks intended for use with the modified form of device shown in Fig. 4.

Fig. 6 is a top plan view of the modified form of device with the attached disks shown in opened-out relation.

In each form of the invention herein illustrated, the ornament is made from a plurality of vertical disks of thin paper joined together along a common central axis, and adapted to form a spherical ball-shaped figure when opened out from the attaching line or axis. The disks are punched out to form an outer circular ring, a vertical bar, and a pair of horizontal cross bars between which are located a series of figures simulating dolls. Each of the two cross bars

is slotted to permit the insertion of a horizontal cross disk. These cross disks serve to stiffen the structure of the ball and also to retain the vertical disks in evenly spaced relation when opened out.

The cross disks will preferably be of somewhat stiff paper or thin cardboard, and the ornamental disks will preferably be of thin paper, although they may also be made of any other suitable material if desired.

Referring now to the drawing where like reference numerals denote corresponding parts throughout the several views,

Figs. 1 to 3 illustrate the first embodiment of the invention, in which—

12 denotes a series of ornamental disks, punched out to form two pairs of figures 13 representing dolls with joined hands. These figures are separated by central vertical bars 14, through the center lines of which the disks 12 may be secured together by stitches or staples 15. A suspending device 16 consisting of a thread or light wire may be attached to the axis of the assembled disks.

The punched-out disks 12 are preferably formed with a pair of cross bars 17 which are provided with central horizontal slits for the insertion of a pair of cross disks 18. The slits are preferably formed by first punching small holes or slots 19 near the ends of the cross bars 17, and then connecting these holes or slots 19 by slits 20.

In operation, the cross disks 18 will first be inserted into the slits of the cross bars 17, after which the vertical disks 12 may be spread apart and uniformly spaced around the circumference of the cross disks 18. As will be clear, the cross disks 18 will then hold said vertical disks opened out in the shape of an ornamental ball.

Referring now to the second embodiment of the invention illustrated in Figs. 4 to 6, the punched-out vertical disks 12^a which are preferably scalloped on their peripheries, are provided with cross bars 17^a, a vertical bar 14^a, and a series of ornamental figures similar to the corresponding parts of the first form of device shown in Figs. 1 and 3. The cross bars 17^a, however, are cut in such a manner as to leave buttons or locking tongues 21 adapted to enter central holes 22 in cross disks 18^a, as clearly shown in Fig. 5. These buttons or locking tongues 21 serve to prevent the cross disks 18^a from accidentally slipping out of the slits in the

cross bars. The buttons 21 not only retain the cross disks 18^a in the dotted positions shown in Fig. 4, when the disks 12^a are in collapsed position, but also hold them open 5 in the unfolded or spread-out condition, as shown in Fig. 6.

The cross disks 18^a are provided with peripheral notches 23 adapted to engage at their rims and accurately space the vertical 10 disks 12^a, when the latter are opened out, as shown in Fig. 6.

It will be understood that any desired 15 number of ornamental disks or plies (12 and 12^a) may be employed in each ornament, within the spirit of the invention, although eight of said disks or plies, as shown in the drawing, are preferred. It will also be understood that the disks or plies may all be made of the same color, or if desired, 20 disks of more than one color may be employed to produce a variegated effect. Moreover, any desired number of cross bars 17 or 17^a, with a corresponding number of cross disks, may be employed, although two 25 cross bars will usually be sufficient to properly stiffen the device and retain the unfolded ornamental sheets in place.

From the foregoing it will be seen that 30 the invention provides simple but effective means for producing inexpensive suspended ornaments for different decorative purposes, such as for Christmas trees, dance halls, verandas, chandeliers, etc., while a ball or spherical form of ornament has been 35 illustrated, other forms may be substituted if desired, and as determined by the form of the punched-out ornamental sheets of which they are composed.

While there have been disclosed in this 40 specification two forms in which the invention may be embodied, it is to be understood that these forms are shown for the purpose of illustration only, and that the invention is not to be limited to the specific disclosures but may be modified and embodied in 45 various other forms without departing from its spirit. In short, the invention includes all the modification and embodiments coming within the scope of the following claims.

Having thus fully described the invention, what is claimed as new, and for which it is desired to secure Letters Patent, is:

1. In a collapsible ornament, a series of 55 sheets secured together along an axis, said sheets having aligned slits, and a stiffening strip to be inserted in said slits for holding the sheets in spaced relation.

2. In a collapsible ornament, a series of 60 sheets joined along a common axis, said sheets having slits perpendicular to said axis, and means extending transversely through 65 said slits for holding said sheets in spaced relation.

3. In a collapsible ornament, a series of 65 disks joined along a common axis, said disks

having slits perpendicular to said axis, and means extending transversely through said slits for holding said disks in spaced relation.

4. In a collapsible ornament, a series of 70 disks joined along a common axis, said disks having slits perpendicular to said axis, and cross disks extending transversely through 75 said slits for holding said disks in spaced relation.

5. In a collapsible ornament, a series of 80 disks joined along a common axis, said disks having slits perpendicular to said axis, and cross disks extending transversely through 85 said slits for holding them in spaced relation, said cross disks having peripheral notches for engaging and uniformly spacing said disks when the ornament is in opened-out position.

6. An ornament composed of a number of 90 plies of thin flexible material with punched-out portions affording ornamental figures, 95 said plies being attached together on a central line or axis from which they may be spread apart, and said plies being provided with slotted cross bars, combined with cross bars to be inserted in said slotted cross bars to hold the ornamental plies in place when opened out.

7. An ornament composed of a number of 100 plies of thin flexible material with punched-out portions affording ornamental figures, 105 said plies being attached together on a central line or axis from which they may be spread apart, and said plies being provided with slotted cross bars, combined with cross disks to be inserted in said slotted cross bars to hold the ornamental plies in place when opened out, said cross bars being provided with tongues and said cross disks being provided with central openings to receive said tongues.

8. An ornament composed of a number of 110 plies of thin flexible material with punched-out portions affording ornamental figures, 115 said plies being attached together on a central line or axis from which they may be opened out, and said plies being provided with slotted cross bars, combined with cross disks to be inserted in said slotted cross bars to hold the ornamental plies in place when opened out, said cross disks having notches at their peripheries for engaging the ornamental plies when said plies are opened out.

9. An ornamental paper ball composed of 120 a number of circular paper disks with punched-out portions affording ornamental figures, 125 said disks being attached together on a central line or axis from which they may be opened out, and said disks being provided with slotted cross bars, combined with cross disks to be inserted in said slotted cross bars to hold the ornamental disks in place when opened out to form a ball-like ornament.

10. An ornamental paper ball composed of a number of circular paper disks with punched out portions affording ornamental figures, said disks being attached together on a central line or axis from which they may be opened out, and said disks being provided with slotted cross bars, combined with cross disks to be inserted in said slotted cross bars to hold the ornamental disks in place when opened out to form a ball-like ornament, said cross bars being provided with central openings to receive said tongues.
11. An ornamental paper ball composed of
- 15 a number of circular paper disks with

punched-out portions affording ornamental figures, said disks being attached together on a central line or axis from which they may be opened out, and said disks being provided with slotted cross bars, combined with 20 cross disks to be inserted in said slotted cross bars to hold the ornamental disks in place when opened out to form a ball-like ornament, said cross disks having notches at their peripheries for engaging and spacing 25 the ornamental disks when said disks are opened out.

In testimony whereof, I have affixed my signature to this specification.

LARS WM. THORSELL.
